LOUIS J. STILLING, OF NEWARK, NEW JERSEY.

SURGICAL IRRIGATING APPARATUS.

1,112,168.

Specification of Letters Patent. Patented Sept. 29, 1914.

Application filed August 1, 1913. Serial No. 782,403.

To all whom it may concern:

Be it known that I, LOUIS J. STILLING, a citizen of the United States, residing at Newark, in the county of Essex and State of New Jersey, have invented certain Improvements in Surgical Irrigating Apparatus, of which the following is a specification.

The objects of this invention are to prevent back flow of gas in an apparatus of this sort to and through the supply of medicinal preparation being administered to the patient; to trap and vent such gas before it has come in contact with the supply; to thus keep the medicinal preparation unchanged and uncontaminated; to provide means for doing this automatically and without the attention of the nurse; to provide such a device which may be readily cleaned and maintained in a sanitary condition; to secure simplicity of construction and operation, and to obtain other advantages and results as may be brought out in the following description.

Referring to the accompanying drawings, in which like numerals of reference indicate the same parts throughout the several views, Figure 1 is an elevation of my improved surgical irrigating apparatus with parts in section; Fig. 2 is a detail elevation of the regulating and observing valve and trap, and Fig. 3 is a longitudinal sectional view of the same.

In the specific embodiment of the invention illustrated in said drawings, the reference numeral 1 indicates a retaining receptacle for the medicinal preparation or fluid 2, said receptacle preferably being provided with only a single opening 6, and that at its bottom. By inverting the receptacle, the same may be filled and the opening 6 closed by any suitable means, such as a plug or cork 7. Passing through this cork 7 is a tube 8 which extends upwardly within the receptacle adjacent to its top and will admit air to compensate for such fluid as may be drawn out and maintain a constant atmospheric pressure on top of the fluid so the same will flow steadily and even.

The fluid is adapted to be drawn off or flow through a second tube 9 which projects through the cork and terminates at the bottom of the receptacle. The lower end of this tube is shown as provided with a knob or nipple-shaped extremity over which a rubber tube 10 may be affixed, the lower end of this rubber tube being similarly secured to

the nippled upper end 11 of my improved flow device 12.

A neck 13 extending centrally upward from a transverse valve 14 connects the same with the nipple or upper end 11 above referred to, and a depending neck 15 below said valve in axial alinement with the upper neck 13 extends at its lower portion into a sight chamber 16. This sight chamber 16 contracts at its lower end and provides a lower nipple 17 onto which may be slipped a rubber or other flexible tube 18 into the lower end of which may be inserted any surgical implement or the like 19 which the exigencies of any particular patient may require. Preferably the chamber 16 is tapered, as shown, at its upper and lower ends to prevent the lodgment or accumulation of gas or the like and facilitate its up-passage to vent means hereinafter more fully described.

The valve 14 preferably comprises a transverse frusto-conical valve seat 20 in which seats a correspondingly frusto-conical revolute member 21 having a knob or other suitable means 22 at the larger end of itself to project outside of the seat and providing means whereby said revolute member may be turned. A passage 23 transversely through the revolute member adapted to be brought, by twisting said member, into registration and axial coincidence with interior longitudinal passages 24, 25 of the upper and lower necks 13, 15, respectively, admits the flow therethrough when desired, and by turning said member partly or entirely out of registration with the stationary passages 24, 25 the flow may thereby be regulated or entirely discontinued at will.

As a means for retaining the revolute member seated, I provide an exterior bead 26 at the larger end of the valve seat. A bow clip 27 placed on the valve adjacent said bead 26 is prevented from slipping off thereby and is provided with laterally extending spring fingers 28, 28 extending over said bead and at either side of the revolute member, engaging an outwardly facing shoulder 39 therein and by virtue of their resiliency pressing against the same and normally forcing said revolute member inwardly, thus causing it to seat.

Within the sight chamber 16 at its upper end, the passage 25 through the neck 15 theretofore contracts into a nozzle 29 which extends downwardly within the chamber and

terminates intermediate of its ends and spaced a distance from the side wall thereof. The lower opening 30 of said nozzle 29 is preferably comparatively restricted as shown, so that the fluid passing therethrough may be caused to leave the nozzle in drops when so desired and also in order that gases entering the sight chamber from below will not readily enter said passage to escape 10 through the fluid contained in the receptacle.

In order to provide for the escape of such gases, I provide above the level of the nozzle opening 30 a vent 31 through the exterior wall of the sight chamber 16. As 15 shown, it is preferable to position this vent at the extreme upper end of the chamber, to eliminate any pockets in which undesirable gases may lodge and avoid as far as possible the likelihood of the fluid finding 20 an exit therethrough. It is to be understood that the removal of these gases is an important feature of the present invention, as to allow them to pass through the medicinal preparation in the receptacle tends to 25 contaminate or abate the preparation by virtue of the solubility of the gases therein or their power to chemically combine with the preparation. Both of these ill effects are largely eliminated by my vent as shown. 30 Said vent, furthermore, is preferably curved so as to open to the atmosphere toward the side, and thus settling dust and the like will not enter into nor stop the passage.

It will be obvious that the operation of 35 my improved apparatus maintains the fluid under perfect control and observation at all times, the several parts are readily accessible and may be easily cleaned and kept sanitary, and contamination during use is eliminated. It is to be understood, however, in 40 describing the various parts of this particular disclosure herein given as illustrative of my invention, I do not wish to be understood as limiting myself thereto except as may be required by the following claims when construed in the light of the prior art.

Having thus described the invention, what I claim is—

1. The herein-described surgical irrigating 50 feed device, comprising a tubular body portion adapted at its upper and lower ends to connect with inlet and outlet pipes and having an upper neck portion and a lower enlarged chamber, a nozzle forming a continuation of said neck and depending into said chamber, the tip of said nozzle being at a distance from the bottom of the chamber so that the level of liquid is below it and the wall of the body portion having a vent 55 opening at the top of the chamber outside the nozzle, and a controlling valve in said

neck, whereby the flow of liquid through the feed device may be observed and any back-flow of gas into the chamber will be trapped and discharged into the atmosphere. 65

2. The herein-described surgical irrigating feed device, comprising a tubular body portion adapted at its upper and lower extremities to receive rubber tubing and having an upper neck portion and a lower enlarged 70 chamber inwardly tapered at its top and bottom, a nozzle forming a continuation of said neck and depending into said chamber from its tapered upward part, the tip of said nozzle being at a distance from the bottom of the chamber so that the level of liquid is below it and the wall of the body portion having a vent opening at the top of the contracting space between the nozzle and the wall of the chamber, and a controlling valve in said neck, whereby the flow of liquid through the feed device may be observed and any back-flow of gas into the 75 chamber will be trapped and discharged into the atmosphere. 80

3. The herein-described surgical irrigating feed device, comprising a tubular body portion adapted at its upper and lower ends to connect with inlet and outlet pipes and having an upper neck portion and a lower enlarged chamber with a nozzle forming a continuation of said neck and depending into said chamber, the tip of said nozzle being at a distance from the bottom of the chamber so that the level of liquid is below it 95 and the wall of the body portion having a vent opening at the top of the chamber outside the nozzle, whereby any back-flow of gas into the chamber will be trapped and discharged into the atmosphere. 100

4. The herein-described surgical irrigating feed device, comprising a tubular body portion adapted at its upper and lower extremities to receive rubber tubing and having an upper neck portion and a lower enlarged chamber inwardly tapered at its top and bottom with a nozzle forming a continuation of said neck and depending into said chamber from its tapered upward part, the tip of said nozzle being at a distance from the bottom of the chamber so that the level of liquid is below it 110 and the wall of the body portion having a vent opening at the top of the contracting space between the nozzle and the wall of the chamber, whereby any back-flow of gas into the chamber will be trapped and discharged into the atmosphere. 115
